UNITED STATES PATENT OFFICE.

PHILIP RAUCH, OF BRADFORD, PENNSYLVANIA.

NOISE-MUFFLER.

SPECIFICATION forming part of Letters Patent No. 734,749, dated July 28, 1903.

Application filed August 28, 1902. Serial No. 121,319. (No model.)

To all whom it may concern:

Be it known that I, PHILIP RAUCH, a citizen of the German Empire, residing at Bradford, in the county of McKean and State of Pennsylvania, have invented certain new and useful Improvements in Noise-Mufflers for Automobiles, &c., of which the following is a specification.

The present invention relates to mufflers used on gas-engines, and is designed to obviate the objectionable noises coincident with the successive explosions of the fuel-gases. In automobiles and motor-bicycles it is essential that the engines and their appurtenances be of the least weight and occupy the least space commensurate with their strength and efficiency. My improved muffler belonging to the latter category fulfills these conditions.

The invention consists of a noise-muffler comprising a central main supply-tube provided with a series of perforations in its wall, means for closing the outer end of said supply-tube, a plurality of cup-shaped muffler-plates arranged in pairs on said supply-tube, so as to form a series of interior muffling-chambers communicating with said perforations, said muffler-plates being provided with small exit-passages and extension-flanges on some of said muffler-plates at their circumference, said flanges being also provided with small exit-passages and forming an exterior series of muffling-chambers communicating with and surrounding the interior series of chambers, as will be fully described herein-after and finally pointed out in the claims.

In the accompanying drawings, Figure 1 shows a vertical central section of my improved muffler on line 1 1, Fig. 2. Fig. 2 is a plan view of the muffler, and Fig. 3 is a horizontal section on line 3 3, Fig. 1.

Similar letters of reference indicate corresponding parts.

Referring to the drawings, C is a pipe screw-threaded at each end and provided with perforations c.

J L N are cup-shaped muffler-plates, and I K M are similar cup-shaped plates, but provided with flanges. These plates are provided each at its center with an opening, so as to be placed upon the pipe C, and are used in the condition in which they come from the

foundry—that is, rough-edged, as indicated in the drawings. Placing these plates upon the pipe one superposed upon the other they 55 form muffling-chambers, and as the exit-openings, due to the irregularity of the edges, are very small the efflux of the gases and sound is considerably retarded.

P indicates a hollow cylinder open at one 60 end and having a circular opening in its closed end, through which passes the pipe C. T is a hollow cylinder also open at one end, having a hole in its closed end, through which passes the pipe C. These cylinders are placed 65 so that their open ends face each other. Suitable coupling-joints consisting of a union A, screwed upon the pipe C at its upper or inlet end and projecting therefrom, so as to be fastened to the exhaust-pipe of the motor, and 70 a cap B hold these plates and cylinders together by pressure and form thereby the noise-muffler.

The path of the gases and of the sound may be described thus: The muffler being attached to the motor by the screw-threaded union A, the successive audible and noisy explosions take place in the cylinder of the motor, and the exhaust-gases and sound due to these explosions pass from the cylinder to 80 the pipe C and pass through the perforations c to the separate chambers D, E, and F. Due to the small openings d, where the rough edges of the castings meet, the sound is considerably retarded. Passing into the second series of muffling-chambers G and H it is again considerably retarded by the small openings g, and, finally, after passing along the circuitous path in the chambers R and S, as indicated by the arrows, the exhaust-gases leave 90 the muffler, but the noise due to the successive explosions is completely muffled. The sound has been damped in its course five times without back pressure, as the cross-section of the exit for the gases is smaller by 95 far than the cross-section of the muffler-plate.

It is obvious that for smaller motors a less number of muffler-plates may be employed and the parts of the muffler reduced in size, while for larger motors a larger number of 100 plates up to any required number may be used.

Z indicates a small discharge-cock communicating with the interior of the supply-tube

and with the outer atmosphere. This cock permits the direct escape of such quantity of the waste gases as may be desired. It is obvious that this cock may be omitted and 5 an entirely-closed cap employed for the lower end of the supply-tube in case no direct escape of the gases is desired.

Having thus described my invention, I claim as new and desire to secure by Letters 10 to Patent—

1. A noise muffler, consisting of a central main supply-tube provided with a series of perforations in its wall, means for closing the outer end of said supply-tube, a plurality of 15 cup-shaped muffler-plates arranged in pairs on said supply-tube so as to form a series of interior muffling-chambers communicating with said perforations, said muffler-plates being provided with small exit-passages, and ex- 20 tension-flanges on some of said muffler-plates at their circumference, said flanges being also provided with small exit-passages and forming an exterior series of muffling-chambers 25 communicating with and surrounding the interior series of chambers, substantially as set forth.

2. A noise-muffler, consisting of a central main supply-tube provided with a series of perforations in its wall, means for closing the outer end of said supply-tube, a plurality of 30 cup-shaped muffler-plates arranged in pairs on said supply-tube so as to form a series of interior muffling-chambers communicating with said perforations, said muffler-plates being provided with small exit-passages, ex- 35 tension-flanges on some of said muffler-plates at their circumference, said flanges being also provided with small exit-passages and forming an exterior series of muffling-chambers 40 communicating with and surrounding the interior series of chambers, an interior cylinder surrounding the muffler-plates and open at one end, and an exterior cylinder open at one end surrounding said interior cylinder 45 and inverted over the same, substantially as set forth.

3. A noise-muffler, consisting of a central main supply-tube provided with a series of perforations in its wall, means for closing the outer end of said supply-tube, a plurality of 50

cup-shaped muffler-plates arranged in pairs on said supply-tube so as to form a series of interior muffling-chambers communicating with said perforations, said muffler-plates being provided with small exit-passages, ex- 55 tension-flanges on some of said muffler-plates at their circumference, said flanges being also provided with small exit-passages and forming an exterior series of muffling-chambers 60 communicating with and surrounding the interior series of chambers, an interior cylinder surrounding the muffler-plates and open at one end, the closed end of said cylinder being mounted on said central supply-tube, an exterior cylinder open at one end surround- 65 ing said interior cylinder and inverted over the same, the closed end of said exterior cylinder being also mounted on said central supply-tube, and a screw-coupling screwed down upon the supply-tube, at the ingoing end of 70 the same and clamping said muffler-plates and cylinders in position, substantially as set forth.

4. A noise-muffler, consisting of a central main supply-tube provided with a series of 75 perforations in its wall, means for closing the outer end of said supply-tube, a plurality of cup-shaped muffler-plates arranged in pairs on said supply-tube so as to form a series of interior muffling-chambers communicating 80 with said perforations, said muffler-plates being provided with small exit-passages, ex- tension-flanges on some of said muffler-plates at their circumference, said flanges being also provided with small exit-passages and form- 85 ing an exterior series of muffling-chambers communicating with and surrounding the interior series of chambers, and a discharge-cock communicating with the interior of said supply-tube for controlling the direct exhaust 90 of a portion of the waste gases into the atmosphere, substantially as set forth.

In testimony that I claim the foregoing as my invention I have signed my name in presence of two subscribing witnesses.

PHILIP RAUCH.
